(57) **CLAIM**

(22) Filed: **Sep. 19, 2002**

The ornamental design for a wire bobbin for a binding
machine, as shown and described.

(30) **Foreign Application Priority Data**

DESCRIPTION

Mar. 20, 2002 (JP) 2002-007433

FIG. 1 is a perspective view of front and left side of a wire
bobbin for a binding machine showing my new design;
FIG. 2 is a front view thereof;
FIG. 3 is a rear view thereof;
FIG. 4 is a top plan view thereof;
FIG. 5 is a bottom view thereof;
FIG. 6 is a right side view thereof;
FIG. 7 is a left side view thereof; and,
FIG. 8 is a perspective reference view of the condition of the
wire bobbin being attached to the binding machine.
The broken line showing of environment is for illustrative
purposes only and forms no part of the claimed design.
